Primary Examiner — Philip S Hyder*Assistant Examiner* — Keith Frank*(74) Attorney, Agent, or Firm* — Dascentro Intellectual Property Law, P.C.**CLAIM**

The ornamental design for pet food container, as shown and described.

DESCRIPTION

FIG. 1 is an isometric view of the pet food container.

FIG. 2 is a side view of the pet food container.

FIG. 3 is another side view of the pet food container.

FIG. 4 is a bottom view of the pet food container; and,

FIG. 5 is a top view of the pet food container.

The broken lines in the drawings depict portions of the pet food container in which the design is embodied that form no part of the claimed design.

1 Claim, 2 Drawing Sheets
